FUME HOOD

John M. Liptay, Manhasset, N. Y.

Application May 8, 1956, Serial No. 583,542

19 Claims. (Cl. 98—115)

The invention is directed to a novel and serviceable fume hood. One object of the invention is to provide an improved fume hood permitting safer use and operation thereof together with permitting greater accessibility in the matter of bodily adjusting a sloping and unitary imperforate baffle disposed within the fume hood. Another object comprehends a fume hood having a new principle of operation carried into effect upon adjustment of the unitary and sloping baffle for changing the direction of the air flow and velocity of the air flow within the fume hood during operation of the fume hood without the need on the part of anyone touching or entering any part of the interior of the fume hood. Specifically another object of the invention is to provide conveniently accessible control means outside of the hood to permit the operator without entering the inside of the hood to easily and promptly adjust a slidably guided sloping baffle within the hood in the matter of varying the size of fume egress apertures formed in part by the upper and lower margins of the sloping baffle. Another object is concerned with a rectilinearly displaceable imperforate baffle for simultaneously but inversely varying the upper and lower fume egress apertures. Another object resides in the provision of manipulatable control means accessible at the front part and outside of the hood for operating adjustable means for bodily and rectilinearly displacing the sloping baffle. Other important objects and advantages and functional and structural features of the invention will be apparent from the following detailed specification considered in the light of the accompanying drawings wherein:

Fig. 1 is a front view of the fume hood according to my invention, shown partly broken away to illustrate the upper fume exhaust aperture.

Fig. 2 is a horizontal sectional view on the line 2—2 of Fig. 1.

Fig. 3 is an enlarged sectional view on the bent line 3—3 of Fig. 1, illustrating the baffle adjusted to provide exhaust apertures of substantially the same area at the top and bottom of the baffle.

Fig. 4 is a view similar to Fig. 3 exhibiting the linearly guided baffle adjusted to fully close the lower aperture and substantially fully open the upper aperture.

Fig. 5 is a view along the lines of Fig. 4 but with the baffle fully closing the upper aperture and concomitantly fully opening the lower aperture.

Fig. 6 is a sectional view on the line 6—6 of Fig. 3 illustrating the spaced and fixed anterior guide rails to facilitate bodily linear displacement of the baffle.

Fig. 7 is a sectional view on the line 7—7 of Fig. 3 depicting the upper and lower pairs of spaced posterior guide rails likewise cooperating to linearly guide the biased baffle.

Fig. 8 is an enlarged schematic view on the line 8—8 of Fig. 1, showing the control and adjustable means for elevating or lowering the forwardly inclined baffle.

Fig. 9 is a fragmentary perspective rear view of Fig. 8 with the slab or counter removed and with the fulcrum

2

means for the rockable bell crank lever removed from the fixed bracket.

Fig. 10 is an enlarged fragmentary view of the control means for rotating the actuating rod.

Fig. 11 is an enlarged sectional view on the line 11—11 of Fig. 8.

Fig. 12 is a fragmentary exploded perspective view of baffle and yoke which supports the baffle, and

Fig. 13 is an enlarged fragmentary view on the line 13—13 of Fig. 8.

The fume hood generally designated FH is appropriately mounted on stone slab or counter 10 supported by fixed and spaced sheet metal channels 11 and 12 suitably carried by the front fixed panel 13 and fixed rear wall 14 respectively of the sheet metal cabinet broadly denoted C. Specifically hood FH includes spaced sides 15, rear wall 16, roof 17, and front panel 18. Corner angle irons 19 constitute a frame to which spaced sides 15, rear wall 16, roof 17 and front panel 18 are appropriately secured. It follows that hood FH characterizes a suitable enclosure defining an internal compartment 20 which is open to the atmosphere through relatively large intake opening 21 between counter 10 and panel 18.

Dividing compartment 20 into a work chamber WC and plenum chamber or duct PC is the inclined stone imperforate baffle B which slopes upwardly and forwardly away from rear wall 16. Duct PC thus progressively expands upwardly communicating with fume egress opening 22 interrupting roof 17, and secured to the latter about opening 22 is the exhaust pipe PE containing a conventional fan (not shown).

Baffle B is bodily slideable and is guided in its rectilinear movement by spaced anterior rails R and the spaced upper and lower posterior strips S which also may be considered as rails. Sloping rails R and strips S are fixedly anchored to spaced sides 15 in any well known manner.

Interrupting baffle B medially and along its lower margin is notch 23 (Fig. 12) for reception of bridge 24 of U shaped yoke 25 having upstanding legs 26 closely straddling the anterior and posterior faces of baffle B. Rivets 27 (Figs. 3 and 8) fasten spaced legs 26 to the body of the baffle. Integral with yoke 25 is the depending lifting rod 28 slidably guided in bore 29 of slab 10 and having a lower threaded part 29' (Figs. 9 and 13) adjustably received in the internal threaded bore of rocker or coupling 30 having spaced outwardly convex lips or cams 31. Integral with and depending from rocker or coupling 30 is tongue 32 which is receivable loosely, that is, slidably fitting in guide slot 33 interrupting long leg or arm 34 of bell crank lever broadly designated BL. Holding tongue 32 loosely in place on arm 34 but against accidental removal is the cotter pin 35 having its legs 36 passing through a suitable opening in tongue or lug 32. Spaced cam shaped lips 31 rock on top rectilinear bearing faces 38 (Fig. 13) adjacent slot 33 of the long arm 34. The loose connection just described for coupling 30 in bell crank lever BL permits ease of translating rotational displacement of arm 34 into linear displacement of lifting rod 28 as desired.

Bell crank BL is pivoted on cylindrical shank 40 (Fig. 8) of bolt 41 (Fig. 11). Shank or fulcrum means 40 is held within alined openings 42 in rearwardly projecting lugs 43 of bracket 44 permanently anchored to rear fixed channel 45 of cabinet C. Clamping nut 46 effectively holds bolt 41 fixedly in place across lugs 43.

Short arm 47 of bell crank lever BL has its upper part in the form of a yoke Y (Fig. 11) comprising parallel upstanding and spaced arms or bearings 50 having openings 51 in which the smooth cylindrical portions of shanks 52 of bolts 53 are journaled, that is, rotatably guided, namely, spaced arms 50 of yoke Y are swingably mounted on bolts 53. However, threaded portions 54 of

shanks 52 frictionally, firmly and tightly engage the teeth of internal and alined threaded bores 55 of cylindrical nut 56. In other words, teeth of threaded portions 54 are jammed with teeth of alined bores 55, whereby threaded portions 54 of bolts 53 always move bodily with nut 56 having threaded bore 57 perpendicular to alined threaded bores 55 for adjustably receiving threaded part 58 of actuating rod or shaft 59 having at its front end internally threaded socket 60 which receives externally threaded terminal part of shaft 62 which is integral with crank 63 carrying hand grasping or manipulatable portion 64. Upon rotation of rod 59, nut 56 through action of its fixed bolts 53, drives arms 50 of yoke Y to cause tilting of yoke Y relative to fulcrum means 40.

Cotter pin 63' traverses socket 60 and the threaded part 61 of shaft 62. Consequently if crank 63 be revolved, shaft 59 is rotated in bearing or bushing 65 having its flange 66 clamped against fixed panel 13 of cabinet C by nut 67 bearing against flange 68 of angle iron 69. Flange 68 is appropriately welded to panel 13 to reinforce the latter. Flange 68 includes opening 70 in alinement with opening 71 in panel 13 for convenient reception of bushing 65. To facilitate rotation of shaft or spindle 62 on rotation of crank 63, ball bearing carrier 75 is effectively interposed between annular races 76. Carrier 75 and races 76 are rotatably sustained on shaft 62 between flange 66 of bushing 65 and face 77 of crank 63. Incidentally, shaft or rod 59 is retained against longitudinal axial displacement by bushing 65 which constitutes a stop for socket 60 and also by end face 77 of crank 63 which co-operates with an adjacent race 76 (Fig. 10).

Although the invention has been described in connection with an open type of fume hood, it is to be understood that it is equally applicable to the closed type of fume hood wherein a conventional safety sash (not shown) is slidably mounted for removably closing opening 21 permitting viewing safely any hazardous chemical reactions within the hood.

Operation

If crank arm 63 be rotated, rod 59 is rotated. Consequently circular nut or driving member 56 is displaced along rod 59. It follows that shanks 52 of bolts 53 are correspondingly displaced, in that shanks 52 bodily move with driving nut 56. Since arms 50 of yoke Y are driven by shanks 52 of bolts 53, yoke Y is tiltably displaced. This action causes short arm 47 of bell crank lever BL to be pivoted relative to the fixedly retained fulcrum means or shank 40. If arm 47 be displaced, arm 34 of pivoted bell crank lever BL is correspondingly displaced, since these arms move in unison. Depending upon the direction of rotation of rod 59, displaceable driving nut 56 is shifted either in a direction towards the rear wall 14 (Fig. 8) of cabinet C or away therefrom. If moved away from cabinet C, yoke Y tilts to swing arm 34 downwardly, thereby causing lifting rod 28 to drop. Such action lowers baffle B. If rod 59 be rotated in an opposite direction, driving nut 56 moves towards the cabinet, thus swinging yoke Y to raise arm 34 to lift rod 28 and baffle B is elevated, that is, slidably displaced between guide rails R and S. In actual practice and according to many successful tests effectively carried through prior to filing the application at bar, jamming of nut 56 against threaded portion 58 of the rotatable and adjustable shaft or rod 59 is precluded in that the amplitude of deflection of nut 56, that is, the distance between the highest part of an arc through which nut 56 travels on rotation of manipulatable control means 63, and the middle part of a cord intersecting the extreme limits of such arc is slight and almost insignificant in comparison to the great length of operating rod 59 and such amplitude of deflection in no way affects the proper displacement of nut 56 along rod 59 in the matter of effectively driving at all times the pivoted bell crank lever BL on rotation of control means 63.

In Figs. 1 and 3, baffle B is spaced from top wall 17 to provide the upper egress aperture 80 and is spaced from counter 10 to provide the lower egress aperture 81. These apertures are thus simultaneously regulated or varied by operating the control means, namely, crank 63 for operating actuating rod 59 in the matter of adjustably setting the tiltable bell crank lever BL which permits the supporting means for baffle B, namely, coupling 30, rod 28 and its yoke 25 to be raised or lowered. When raised, arm 34 acts on lips 30 to shift rod 28 upwardly. When arm 34 is lowered, rod 28 together with baffle B fall by gravity. It is thus apparent that control means accessible outside of the hood has been provided for adjusting the tilt of the rockable bell crank lever BL for bodily shifting baffle B to simultaneously but inversely vary the areas or sizes of egress apertures 80 and 81, in other words if imperforate baffle B be adjusted in one direction aperture 80 is made smaller at the same time aperture 81 becomes larger. If baffle B be shifted in an opposite direction, the reverse or opposite is true, namely, aperture 80 becomes larger while aperture 81 grows smaller. By "imperforate" is meant that baffle B is solid and uninterrupted to allow fumes or gases through the body thereof.

25 Fresh air enters through opening 21 of the front wall of hood FH (Fig. 3) into work chamber WC where it is divided into two channels, namely, one channel flows across the upper part of work chamber WC carrying with it the light fumes to upper apertures 80; and the other 30 channel flows across the lower part of the work chamber carrying with it relatively heavy fumes into lower egress aperture 81. After reaching duct PC, the fumes therein are drawn into exhaust conduit FE and then to the atmosphere. By the present arrangement, dead regions within 35 work chamber WC and duct PC where gases might collect are eliminated. The front wall of hood or enclosure FH (Fig. 1) is defined by the front upper panel 18 which is spaced from counter 10 and the front spaced corner angle irons 19. In the specification, the expressions 40 "linear" and "rectilinear" have been employed. These terms each mean straight line direction and consequently may be used interchangeably. The length of compartment WC should be considered as the distance between the spaced sides 15 of the fume hood (Fig. 2).

45 Where desirable, baffle B may be set to fully open upper egress aperture 80 and simultaneously fully close off lower aperture 81 as illustrated in Fig. 4 where relatively light fumes are shown passing from beaker 90 to upper aperture 80. Conversely in Fig. 5, upper aperture 80 50 is shut off and lower aperture 81 is fully open in which case, heavy fumes emanating from beaker 90 flow to lower aperture 81. During operation of the fume hood and through actuation of crank 63, baffle B may be adjusted to simultaneously vary the size of upper and lower 55 apertures 80 and 81 and even to sizes of apertures between the extreme limits illustrated in Figs. 4 and 5.

Slidable and sloping baffle B extends almost fully across the length of the internal compartment, that is, the distance between spaced sides 15 of enclosure FH. 60 Baffle B also extends across the entire height of the enclosure, that is, the distance between counter 10 and top wall 17 except of course for the combined heights of apertures 80 and 81. Note Figs. 2, 3, 6 and 7. Baffle B may be said to be interposed between the front air intake opening 21 and the fume exhaust opening 22, the latter may be considered to be spaced from and to the rear of the front opening 21.

Rotatable rod 59, nut 56 and its bolts 53 together with pivoted bell crank lever BL in fact constitute adjustable 70 operative means for automatically raising or lowering of the baffle supporting means constituted by yoke 25 and its depending portion 28 upon rotation of control means 63.

Stated in another way, metal operating rod or shaft 75 59 is adequately retained against longitudinal displace-

ment except for inevitable manufacturing tolerances and clearances allowing usual and slight play although shiftable nut or barrel 56 during its displacement along shaft 59 causes flexing of this shaft however just slightly to compensate for arcuate displacement of nut 56 thereby preventing nut 56 jamming against shaft 59.

Various changes may be made in details of construction and arrangement of parts without departing from the spirit of the invention or sacrificing any of the advantages thereof inherent therein.

I claim:

1. In a fume hood, an enclosure adapted to be seated on a counter of a cabinet and defining therewith a compartment and having spaced sides and a rear wall and having a front wall including a relatively large air intake opening to permit access to apparatus on said counter and to permit air to enter said compartment and having a top wall including a fume exhaust opening at the rear thereof, a sloping movably arranged imperforate baffle within said enclosure and interposed between and spaced from said openings and having its upper part disposed in advance of said exhaust opening and having its lower part spaced from said rear wall a distance less than the distance between said upper part and said rear wall, said baffle extending almost fully across the length of said compartment between said sides to direct fumes towards said top wall and/or counter and dividing said compartment into a work chamber for containing said apparatus and an upwardly expanding exhaust duct in communication with said exhaust opening and defining with said sides and top wall and with said counter upper and lower apertures in communication with said duct and chamber for receiving said fumes from said chamber for reception into said duct during operation of said hood, said sloping baffle being of a height substantially commensurate with the height of said work chamber except for the heights of said apertures, guide means within said enclosure and secured to said sides for directing linearly and bodily displacement of said baffle, and means for adjustably and bodily displacing said baffle for simultaneously regulating the sizes of said apertures during the operation of said fume hood.

2. In a fume hood, an enclosure adapted to be seated on a counter of a cabinet and defining therewith a compartment and having spaced sides and a rear wall and having a front wall including a relatively large air intake opening to permit access to apparatus on said counter and to permit air to enter said compartment and having a top wall including a fume exhaust opening at the rear thereof, a sloping movably arranged imperforate baffle within said enclosure and interposed between and spaced from said openings and having its upper part disposed in advance of said exhaust opening and having its lower part spaced from said rear wall a distance less than the distance between said upper part and said rear wall, said baffle extending almost fully across the length of said compartment between said sides to direct fumes towards said top wall and/or counter and dividing said compartment into a work chamber for containing said apparatus and an upwardly expanding exhaust duct in communication with said exhaust opening and defining with said sides and top wall and with said counter upper and lower apertures in communication with said duct and chamber for receiving said fumes from said chamber for reception into said duct during operation of said hood, said sloping baffle being of a height substantially commensurate with the height of said work chamber except for the heights of said apertures, spaced guide means within said enclosure and secured to said sides for directing linearly and bodily displacement of said baffle, adjustable means for bodily displacing said baffle for simultaneously but inversely varying the sizes of said apertures during the operation of said fume hood, and control means outside of said enclosure for actuating said adjustable means.

3. In a fume hood, an enclosure adapted to be seated on a counter of a cabinet and defining therewith a compartment and having spaced sides and a rear wall and having a front wall including a relatively large air intake opening to permit access to apparatus on said counter and to permit air to enter said compartment and having a top wall including a fume exhaust opening at the rear thereof, a sloping movably arranged imperforate baffle within said enclosure and interposed between and spaced from said openings and having its upper part disposed in advance of said exhaust opening and having its lower part spaced from said rear wall a distance less than the distance between said upper part and said rear wall, said baffle extending almost fully across the length of said compartment between said sides to direct fumes towards said top wall and/or counter and dividing said compartment into a work chamber for containing said apparatus and an upwardly expanding exhaust duct in communication with said exhaust opening and defining with said sides and top wall and with said counter upper and lower apertures in communication with said duct and chamber for receiving said fumes from said chamber for reception into said duct during operation of said hood, said sloping baffle being of a height substantially commensurate with the height of said work chamber except for the heights of said apertures, spaced guide means within said enclosure and carried by said sides for directing linearly and bodily displacement of said baffle, adjustable means outside of and below said enclosure and carried by said cabinet for bodily displacing said baffle for simultaneously but inversely varying the sizes of said apertures during the operation of the said fume hood, and control means near said front wall and below said counter and outside of said enclosure for actuating said adjustable means.

4. In a fume hood having a counter, an enclosure seated on said counter and provided with an air intake opening and a fume exhaust opening spaced from said intake opening, a sloping and slidable baffle extending across and disposed within said enclosure and spaced from and interposed between said openings, guide means within said enclosure for directing linearly and bodily displacement of said sloping baffle, a rotatable shaft disposed outside of said enclosure and having a threaded portion, means retaining said shaft against longitudinal axial displacement, displaceable driving means having means threadably engaging said threaded portion, a pivoted bell crank lever having a pair of spaced arms, means carried by said driving means for swingably shifting one of said arms, supporting means secured to said baffle and having depending means, a coupling adjustably secured to said depending means and having cam means movably seated on the other arm of said pair, said last mentioned arm and coupling having a loose connection therebetween, and control means outside of said enclosure for rotating said shaft to displace said driving means to tilt said lever for bodily elevating or lowering of said supporting means and baffle.

5. In a fume hood having a counter, an enclosure seated on said counter and provided with an air intake opening and a fume exhaust opening spaced from said intake opening, a sloping and slidable imperforate baffle extending across and disposed within said enclosure and spaced from and interposed between said openings, guide means within said enclosure for directing linearly and bodily displacement of said sloping baffle, a rotatable shaft disposed outside of said enclosure and having a threaded portion, means retaining said shaft against longitudinal axial displacement, displaceable driving means having means threadably engaging said threaded portion, a pivoted bell crank lever having a yoke and an arm diverged from said yoke, means carried by said driving means for swingably shifting said yoke for pivotally displacing said lever, supporting means secured to said baffle and having depending means, a coupling adjustably secured to said depending means and having cam means

movably seated on said arm, said arm having a slot and said coupling having a lug loosely guided in said slot, means to preclude removal of said lug from said slot, and control means outside of said enclosure for rotating said shaft to displace said driving means to tilt said lever for bodily elevating or lowering of said supporting means and baffle.

6. In a fume hood, an enclosure adapted to be seated on a counter and defining therewith a compartment and having spaced sides and a rear wall and having a front wall including a relatively large intake opening to permit access to apparatus on said counter and to permit air to enter said enclosure and having a top wall including a fume exhaust opening, a slidable imperforate baffle spaced from said front and rear walls and extending substantially fully across said compartment between said sides to define an aperture with a part of said enclosure and at least in part dividing said compartment into a work chamber in communication with said intake opening and aperture and an exhaust duct in communication with said aperture and said exhaust opening, displaceable supporting means carrying said baffle, spaced means carried by said sides and within said enclosure for bodily and rectilinearly guiding said baffle, operative means cooperating with said supporting means for bodily and linearly displacing said baffle relative to said counter for adjusting said aperture, manipulatable control means for actuating said operative means, and means to guide said supporting means.

7. A fume hood for cooperating with a counter comprising an enclosure defining with said counter a compartment and having a front wall including an air intake opening and having an upper part including a fume exhaust opening spaced from said intake opening, a movable imperforate baffle within said enclosure and sloping relative to said counter and interposed between and spaced from said intake and exhaust openings and dividing said compartment into a work chamber in communication with said intake opening and an upwardly expanding duct in communication with said exhaust opening, said sloping baffle having an upper longitudinal marginal portion defining with the upper part of said enclosure an upper aperture in communication with said chamber and duct and having a lower longitudinal marginal portion defining with the lower part of said enclosure and said counter a lower aperture in communication with said chamber and duct, means bodily and rectilinearly guiding said sloping baffle, operative means for bodily shifting said baffle to vary simultaneously but inversely the sizes of said apertures, and control means for actuating said operative means.

8. A fume hood for cooperating with a counter comprising an enclosure defining with said counter a compartment having a front wall including an air intake opening and having a top wall including a fume exhaust opening spaced from said intake opening, a movable imperforate one piece inclined baffle within said enclosure and sloping relative to said counter and interposed between and spaced from said intake and exhaust openings and dividing said compartment into a work chamber in communication with said intake opening and an upwardly expanding duct in communication with said exhaust opening, said inclined baffle having an upper longitudinal marginal portion defining with said top wall an upper aperture in communication with said chamber and duct and having a lower longitudinal marginal portion defining with the lower part of said enclosure and said counter a lower aperture in communication with said chamber and duct, means carried by said enclosure for bodily and rectilinearly guiding said sloping baffle, operative means for bodily shifting said baffle to vary simultaneously but inversely the sizes of said apertures, and rotatable control means for actuating said operative means.

9. A fume hood for cooperating with a counter com-

prising an enclosure defining with said counter a compartment and having a front wall including an air intake opening and having a top wall including a fume exhaust opening spaced from said intake opening, a movable imperforate inclined baffle within said enclosure and sloping relative to said counter and interposed between and spaced from said intake and exhaust openings and dividing said compartment into a work chamber in communication with said intake opening and an upwardly expanding duct in communication with said exhaust opening, said inclined baffle having an upper longitudinal marginal portion defining with said top wall an upper aperture in communication with said chamber and duct and having a lower longitudinal marginal portion defining with the lower part of said enclosure and said counter a lower aperture in communication with said chamber and duct, means carried by said enclosure for bodily and rectilinearly guiding said sloping baffle, supporting means carrying said baffle, operative means to displace said supporting means for bodily shifting said baffle to vary simultaneously the sizes of said apertures, and control means outside of said enclosure for actuating said operative means.

10. A fume hood for cooperating with a counter comprising an enclosure defining with said counter a compartment and having a front wall including an air intake opening and a top wall including a fume exhaust opening spaced from said intake opening, a movable imperforate inclined baffle within said enclosure and sloping relative to said counter and interposed between and spaced from said intake and exhaust openings and dividing said compartment into a work chamber in communication with said intake opening and an upwardly expanding duct in communication with said exhaust opening, said inclined baffle having an upper longitudinal marginal portion defining with said top wall an upper aperture in communication with said chamber and duct and having a lower longitudinal portion defining with the lower part of said enclosure and said counter a lower aperture in communication with said chamber and duct, means carried by said enclosure for bodily and rectilinearly guiding said sloping baffle, operative means for bodily shifting said baffle to vary the sizes of said apertures, and manipulatable control means outside of said enclosure for actuating said operative means, said baffle extending almost fully across the length of said compartment and extending across the height of said compartment except for the heights of said apertures.

11. A fume hood comprising an enclosure adapted to be seated on a counter to define therewith a compartment and including a front wall having a relatively large air intake opening and having a top wall including a fume exhaust opening to the rear of and spaced from said intake opening, an inclined movably disposed imperforate baffle interposed between and spaced from said openings and arranged within said compartment and dividing the latter into a work chamber and an upwardly expanding duct and defining with said enclosure and counter upper and lower apertures in communication with said work chamber and duct, spaced guide means within and carried by said enclosure for rectilinearly and bodily directing displacement of said baffle, movable supporting means fixedly carrying said baffle, operative means coacting with said supporting means to bodily raise or lower said baffle relative to said counter and enclosure to vary the sizes of said apertures, and control means to actuate said operative means, said baffle extending almost fully across the length of said compartment and extending across the height of said compartment except for the combined heights of said apertures.

12. A fume hood comprising an enclosure adapted to be seated on a counter to define therewith a compartment and including a relatively large air intake opening and a fume exhaust opening to the rear of and spaced

from said intake opening, a sloping movably disposed imperforate baffle interposed between and spaced from said openings and arranged within said compartment and dividing the latter into a work chamber and an upwardly expanding duct and defining with said enclosure and counter upper and lower apertures in communication with said work chamber and duct, guide means for rectilinearly and bodily directing displacement of said baffle, supporting means in part disposed within and in part outside of said enclosure and carrying said baffle, movable operative means for actuating said supporting means to bodily raise or lower said baffle relative to said counter and enclosure to simultaneously vary the sizes of said apertures, and control means to actuate said operative means.

13. A fume hood comprising an enclosure adapted to be seated on a counter to define therewith a compartment and including a relatively large air intake opening and a fume exhaust opening to the rear of and spaced from said intake opening, a sloping movably disposed imperforate baffle interposed between and spaced from said openings and arranged within said compartment and dividing the latter into a work chamber and an upwardly expanding duct and defining with said enclosure and counter upper and lower apertures in communication with said work chamber and duct, guide means for rectilinearly and bodily directing displacement of said baffle, adjustable operative means outside of said enclosure, supporting means carrying said baffle and seated on a part of said operative means for bodily raising or lowering said baffle relative to said enclosure to simultaneously vary the sizes of said apertures, and control means outside and at the front part of said hood and outside of said enclosure to actuate said adjustable means.

14. In a fume hood, an enclosure adapted to be seated on a counter and defining therewith a compartment and having spaced sides and a rear wall and having a front wall including a relatively large air intake opening to permit access to apparatus on said counter and to permit air to enter said compartment and having a top wall including a fume exhaust opening at the rear thereof, a sloping movably arranged imperforate baffle within said enclosure and having its upper part spaced from but disposed in advance of said exhaust opening and having its lower part spaced from said rear wall a distance less than the distance between said upper part and said rear wall, said baffle extending almost fully across the length of said compartment between said sides to direct fumes towards said top wall and/or counter and dividing said compartment into a work chamber for containing said apparatus and an upwardly expanding exhaust duct in communication with said exhaust opening and defining with said sides and top wall and with said counter upper and lower apertures in communication with said duct and chamber for receiving said fumes from said chamber, spaced guide means within said enclosure for rectilinearly and bodily directing displacement of said baffle, operative means to bodily raise or lower said baffle relative to said counter and enclosure to vary the sizes of said apertures, and manipulatable control means outside of said enclosure to actuate said operative means, said sloping baffle extending fully across the height of said compartment except for the combined heights of said apertures.

15. A fume hood comprising an enclosure adapted to be seated on a counter to define therewith a compartment and including an air intake opening and a fume exhaust opening spaced from said intake opening, a movable support, a sloping imperforate baffle within said enclosure and exposed to said intake opening but interposed between and spaced from said openings and dividing said enclosure into a work chamber and an upwardly expanding duct and defining with said enclosure and counter upper and lower apertures in communication with said work chamber and duct, means securing the lower part of said baffle to said movable support, spaced means fixed

to said enclosure for bodily and rectilinearly guiding said sloping baffle along the height of said enclosure, said baffle occupying almost the entire length of said enclosure and extending along the entire height of said chamber except for the combined heights of said apertures, adjustable operative means for raising or lowering said support relative to said counter and enclosure for bodily raising or lowering of said baffle along the height of said compartment to simultaneously but inversely vary the sizes of said apertures, control means outside of said enclosure to actuate said operative means, and means for movably guiding said support.

16. A fume hood comprising an enclosure adapted to be seated on a counter to define therewith a compartment and including a relatively large air intake opening and a fume exhaust opening to the rear of and spaced from said intake opening, a sloping movably disposed imperforate baffle interposed between and spaced from said openings and arranged within said compartment and dividing the latter into a work chamber and an upwardly expanding duct and defining with said enclosure and counter upper and lower apertures in communication with said work chamber and duct, guide means for rectilinearly and bodily directing displacement of said baffle, said baffle extending substantially fully across the length of said compartment and extending fully across the height of said compartment except for the heights of said apertures, a rotatable rod, means retaining said rod against longitudinal axial displacement, driving means mounted on said rod, said rod and driving means having means for displacing said driving means on rotation of said rod, a pivoted bell crank lever, said driving means having means to actuate said lever upon displacement of said driving means, a movable support carrying said baffle, means for displacing said support upon displacement of said lever, and control means for rotating said rod.

17. A fume hood comprising an enclosure adapted to be seated on a counter to define therewith a compartment and including a relatively large air intake opening and a fume exhaust opening to the rear of and spaced from said intake opening, a sloping movably disposed imperforate baffle interposed between and spaced from said openings and arranged within said compartment and dividing the latter into a work chamber and an upwardly expanding duct and defining with said enclosure and counter upper and lower apertures in communication with said work chamber and duct, guide means for rectilinearly and bodily directing displacement of said baffle, said baffle extending substantially fully across the length of said compartment and extending fully across the height of said compartment except for the combined heights of said apertures, a rotatable rod having a threaded portion, means retaining said rod against longitudinal axial displacement, driving means threadably engaging said portion, a pivoted bell crank lever having a pair of arms, said lever and driving means having means to shift one of said arms for pivotally displacing said lever to tilt the other arm of said pair, a movable support bodily carrying said baffle, means for guiding displacement of said support upon displacement of said lever, means to lift said support upon tilting of said other arm, and control means outside of said enclosure for rotating said rod.

18. A fume hood comprising an enclosure adapted to be seated on a counter to define therewith a compartment and including a relatively large air intake opening and a fume exhaust opening to the rear of and spaced from said intake opening, a sloping movably disposed imperforate baffle interposed between and spaced from said openings and arranged within said compartment and dividing the latter into a work chamber and an upwardly expanding duct and defining with said enclosure and counter upper and lower apertures in communication with said work chamber and duct, guide means for rectilinearly and bodily directing displacement of said baffle, said baffle extending substantially fully across the length of said

compartment and extending fully across the height of said compartment except for the combined heights of said apertures, a rotatable rod having a threaded portion, means retaining said rod against longitudinal axial displacement, driving means threadably engaging said portion, a pivoted bell crank lever having a pair of arms, said lever and driving means having means to shift one of said arms for pivotally displacing said lever to tilt the other arm of said pair, a movable support bodily carrying said baffle and movably seated on said other arm, means for guiding displacement of said support upon displacement of said lever, said other arm and support having means defining a loose connection, and control means for rotating said rod.

19. A fume hood comprising an enclosure adapted to be seated on a counter to define therewith a compartment and including a relatively large air intake opening and a fume exhaust opening to the rear of and spaced from said intake opening, a sloping movably disposed imperforate baffle interposed between and spaced from said openings and arranged within said compartment and dividing the latter into a work chamber and an upwardly expanding duct and defining with said enclosure and counter upper and lower apertures in communication with said work chamber and duct, guide means for rectilinearly and bodily directing displacement of said baffle, said baffle extending substantially fully across the length of said compartment and extending fully across the height of said

compartment except for the combined heights of said apertures, a rotatable rod having a threaded portion, means retaining said rod against longitudinal axial displacement, driving means threadably engaging said portion, a pivoted bell crank lever having a pair of arms, said lever and driving means having means to shift one of said arms for pivotally displacing said lever to tilt the other arm of said pair, a movable support bodily carrying said baffle and having depending means, means for guiding displacement of said depending means upon displacement of said lever, said other arm having means for loosely receiving said depending means, means to preclude removal of said depending means from said other arm, and control means for rotating said rod.
